UNITED STATES PATENT OFFICE.

ROBERT PAGE NEWTON AND THOMAS W. O'KEEFE, OF MIDDLETOWN, CONNECTICUT.

DESIGN FOR A CANDELABRUM.

44,252.

Specification for Design.

Patented June 24, 1913.

Application filed March 20, 1913. Serial No. 755,805. Term of patent 7 years.

To all whom it may concern:

Be it known that we, ROBERT PAGE NEWTON and THOMAS W. O'KEEFE, citizens of the United States, residing at Middletown, in the county of Middlesex and State of Connecticut, have invented a new, original, and ornamental Design for Candelabra, of which the following is a specification, reference being had to the accompanying drawing, forming part thereof.

The figure is a perspective view of our candelabrum.

We claim:

The ornamental design for a candelabrum, as shown.

ROBERT PAGE NEWTON.
THOMAS W. O'KEEFE.

Witnesses:

BERTRAND E. SPENCER,
SHEFFIELD H. CLARKE.
